ATTORNEY

UNITED STATES PATENT OFFICE.

SAMUEL E. WHISNER, OF VERONA, PENNSYLVANIA.

PERFORATION DEVICE FOR WALL-PAPER.

1,072,890.

Specification of Letters Patent.

Patented Sept. 9, 1913.

Application filed March 1, 1913. Serial No. 751,458.

To all whom it may concern:

Be it known that I, SAMUEL E. WHISNER, a citizen of the United States of America, residing at Verona, in the county of Allegheny and State of Pennsylvania, have invented certain new and useful Improvements in Perforation Devices for Wall-Paper, of which the following is a specification, reference being had therein to the accompanying drawing.

This invention relates to a perforating device for wall paper, and the primary object of my invention is to provide an electrically operated device that permits of the border 15 of wall paper being easily and quickly perforated, whereby the useless paper can be easily removed, thereby obviating the tedious and tiresome task of cutting out the border with scissors or a pen knife.

20 A further object of this invention is to provide a simple, durable and inexpensive perforating device embodying an electro-magnet which has the armature thereof provided with a detachable perforating needle 25 located so that a border paper can be passed beneath the needle and the outline of a border perforated.

With the above and other objects in view the invention resides in the novel construction, combination and arrangement of parts 30 to be hereinafter specifically described and then claimed.

Reference will now be had to the drawing, wherein:—

35 Figure 1 is a perspective view of the perforating device, Fig. 2 is a longitudinal sectional view of the same, Fig. 3 is a cross sectional view of the device, and Fig. 4 is a longitudinal sectional view of a modified 40 form of device.

A device in accordance with this invention 45 comprises a box-like metallic casing 1 provided with a detachable bottom plate 2, said bottom plate being flanged, as at 3 whereby it can be secured to the side walls of the casing by screws 4 or other fastening means. Located upon the bottom plate 2, within the casing 1, and insulated from said bottom plate is an electro-magnet 5 and pivotally connected to said electro-magnet, as at 6 is a longitudinal armature 7 that extends through an opening 8 provided therefor in the front wall 9 of the casing 1. The outer end of the armature is bent downwardly, as at 10 and provided with a socket 11 for an adjustable perforating needle 12.

The needle 12 is adjusted through the medium of a set screw 13, which also permits of the needle being removed when dull or broken. The top 14 of the casing 1 has an opening 15 and this opening provides clearance for a tension screw 16 that controls the vibrations of the armature 7. The side walls of the casing 1 are provided with binding posts 17 whereby suitable electrical connections can be made with the electro-magnet 5 from a suitable source of electrical energy. The front wall 9 of the casing 1 has the lower edge thereof provided with parallel guides 18 having the forward ends thereof bent upwardly, as at 19 whereby border paper can be placed beneath said guide arms and easily moved and shifted beneath the perforating needle 12. In some instances the device can be shifted over the border 75 paper and in either instance the perforating is expeditiously and economically performed.

In Fig. 4 of the drawing the electro-magnet is supported from the top of the casing 1 and the armature arranged beneath said electro-magnet, thereby obviating the necessity of bending the outer end of the armature in proximity to the bottom of the casing. In other words it is simply a reversal 80 of the parts within the casing 1 shown in Fig. 2 with the exception of the armature.

When using the device, the operator grasps the casing 1 and moves it longitudinally of the paper to perforate the latter at 90 the border whereby the portion of the paper not desired can be readily severed. Suitable electrical connections are provided to alternately energize and deenergize the magnets to reciprocate the perforating needle 12. 95

The preferred embodiments of the invention have been illustrated but it is to be understood that the structural elements are susceptible to such variations and modifications as fall within the scope of the appended 100 claims.

What I claim is:—

1. An electrical perforating device comprising a casing having one end provided with an opening, a pair of magnets arranged 105 within said casing, an armature projecting through said opening and having each of its ends bent in angular manner, said inner angular end projecting toward one of said magnets, a pin for pivotally connecting said inner angular end to that magnet toward which it projects, a short needle connected 110

- to the outer angular end of the armature, and a pair of spaced guide rods secured to that end of the casing provided with the opening at the bottom of said end.
- 5 2. An electrical perforating device comprising a casing having one end provided with an opening, a pair of magnets arranged within said casing, an armature projecting through said opening and having each of its ends bent in an angular manner, said inner angular end projecting toward one of said magnets, a pin for pivotally connecting said inner angular end to that magnet to-
- 10

ward which it projects, a short needle connected to the outer angular end of the armature, and a pair of spaced guide rods secured to that end of the casing provided with the opening at the bottom of said end, the free ends of said rods curving upwardly.

In testimony whereof I affix my signature 20 in the presence of two witnesses.

SAMUEL E. WHISNER.
